(57) **CLAIM**

I claim the ornamental design for a toy barn figure, as shown and described.

DESCRIPTION

FIG. 1 is a front elevation view of a toy barn figure with the weather vane pointing towards the right.

FIG. 2 is a right side elevation view of a toy barn figure with the weather vane pointing towards the rear.

FIG. 3 is a top plan view of a toy barn figure with the weather vane pointing in the same direction as in FIG. 2; and,

FIG. 4 is a left side elevation view of a toy barn figure with the weather van pointing to the front.
